UNITED STATES PATENT OFFICE

EDMUND O. SCHWEITZER, OF NORTHBROOK, ILLINOIS

ELECTRIC CUT-OUT

Continuation of application Serial No. 460,582, filed June 12, 1930. This application filed September 11, 1931. Serial No. 562,243.

This application is a continuation of my pending application, Serial No. 460,582, filed June 12, 1930. The above application refers to fused cut-outs wherein a fuse is mounted in a chamber containing oil or other insulating liquid, for interrupting a circuit under certain conditions and a switch is mounted in the same chamber for interrupting the same circuit under other conditions. 5

10 It is an object of the present invention to provide an improved casing structure employing an improved bushing structure for extending a conductor thereinto.

The attainment of the above and further 15 objects of the present invention will be apparent from the following specification taken in conjunction with the accompanying drawing forming a part thereof.

In the drawing:

20 Figure 1 is a plan view of my improved cut-out, the cover being removed;

Figure 2 is a view in partial section taken along the line 2—2 of Figure 1, certain of the parts being shown in section and others 25 being shown in elevation;

Figure 3 is a fragmentary sectional view taken along the line 3—3 of Figure 2 and looking in the direction of the arrows;

Figure 4 is a view similar to Figure 3 and 30 showing an alternate form of construction; and

Figure 5 is a fragmentary sectional view of a modified form of bushing construction.

Referring now more particularly to the 35 drawing, the cut-out comprises an open top casing 1 which is adapted to receive the various operating parts and which is filled with insulating oil or other insulating liquid to a level as indicated by the line 2. The 40 casing is provided with a novel bushing structure for leading the line conductors into the casing. Each bushing includes a bushing shield comprising a nipple and insulating sleeve 5 through which the conductor 6 extends.

The nipple is forced through a suitable opening in the casing 1, said nipple making a press fit within the opening. The insulating sleeve 5 having the conductor 6 fitting tightly therein is itself pressed into the 45 nipple 4, said sleeve being pressed upward

into the nipple from the bottom side thereof. The insulator 5 is provided with a flange having an upper tapered surface 7 that seats against a corresponding tapered surface at the inner bottom side of the nipple and limits the extent of inward movement of the insulating sleeve 5 within the casing 1. Since the various parts are press fitted within one another leakage of insulating liquid from 55 within the casing 1 is prevented.

The conductor 6 has a portion 8 extending beyond the insulating sleeve 5, constituting means for establishing a connection with a suitable conductor for extending a circuit through the cut-out. Prior to the making 60 of the connection with the incoming line conductor, a guarding sleeve 10 and a clamping nut 11 are slipped over the end of the conductor and, upon the completion of the 65 electrical connections with portion 8 of the conductor 6 the guarding sleeve is brought up to bear against the flange 6 of the insulator 5, said sleeve and said flange being both provided with cooperating tapered portions forming a conical seat 12. The clamping nut 11 is then threaded to the bottom of the nipple 4 and, at the shoulder 13, it clamps the guarding sleeve 10 and the insulator 5 against the nipple 4 thus effectively securing both of 70 those members against outward withdrawal. A contact terminal 15 having a pair of projecting ears 16 is clamped to the end of the conductor 6 within the casing 1 by means of a suitable screw or bolt 17. The contact 75 15 is tightly clamped around the conductor 6 and it rests against the insulating sleeve 5 thereby preventing the withdrawal of the conductor 6 through the sleeve and out of the casing.

The top of the casing 1 is provided with an inturned circular rim or flange 18 upon which is adapted to be seated a circular disc 19 from which is suspended the various operating parts, and a cover 20. A pad 21, of 80 felt or the like, is interposed between the cover 20 and the flange 18 in order to provide an effective seal to prevent the entrance of moisture or other foreign material into the casing. The cover 20 is bolted to the 85 100

flange 18 by means of six bolts indicated at 22. A block 25 of suitable insulating material is suspended from the top disc 19 by means of four studs 26 which may be locked in place by means of nuts 27. The studs 26 are threaded into corresponding holes in the block of insulation 25 and are locked against turning by nuts 29. Two threaded studs 40 10 extend through openings in the block 25 on opposite sides of the center thereof and are locked thereto by lower nuts 41 and an upper washer 42 and an upper nut 43. The studs 40 are made of copper or other metal of high 15 electric conductivity. Laminated spring contacts 45 are mounted between the lock nut 43 and the washer 42 and are held in firm electrical contact with the stud 40 by means of the nut 43. A pivot member 48 is welded or 20 otherwise secured to the left hand contact spring 45 and a similar member 49 is similarly secured to the right hand contact spring 45. The member 48 is pivoted between two 25 arms of a link 51 by means of a pin 52 which extends through a circular hole in the arms of the member 51 and through a similar hole in the member 48, said member 48 being rotatable with respect to the arms of the link 51. The member 49 is similarly pivoted be- 30tween the two arms of a link 55 similar in construction to the link 51. The two links 51 and 55 are pivotally connected together by means of two pins 56 and 57 located at the opposite sides of the sets of links, said pins 35 extending through holes in the adjacent ends of the links and screwing into a nut 58 that lies between the two arms of the link 51. The nut 58 comprises merely a square block which fits between the two arms of the link 51 and which is provided with a central opening 40 for receiving an operating shaft in a manner to be more fully set forth as the description proceeds. The links 51 and 55 are made of suitable electrical insulating material so as to 45 not to constitute a short circuit between the contact springs 45 and they constitute a toggle for forcing the contacting ends of the springs 45 into engagement with the contact 50 mounted within the casing 1 as previously described. The links 51 and 55 constitute a toggle which is on dead center when the switch is in its closed position, as illustrated, and which is forced to the open position by the action of the spring pressure of the 55 contacts 45 when the toggle is knuckled slightly upward.

An actuating or tripping rod 59 is screw threaded through an internally threaded opening in the member 58, being locked in place by means of a lock nut 60. The lock nut 60 may be omitted if desired. It is to be noted that the block 58 is pivoted between the links so that it may remain horizontal when the toggle breaks.

65 A block 65 of insulating material is sus-

70 pended from the studs 40, and a fuse link 56 is removably mounted on the bottom side of the block 65 by means of a pair of screws 67. To facilitate the making of this connection, the block 65 is provided with a channel-shaped groove 70 formed on its under side, in which I mount a pair of metallic plate members 68 and 69 of suitable conducting material. The studs 40—40 thread into these plates and the compression block 65 rests 75 upon them. The screw members 66 and 67 thread into these blocks to secure the fuse thereto and to establish an electric circuit between the studs 40—40 through the fuse.

75 The block 65 has a cylindrical bore 75 formed therein at its center and extending upwardly from the bottom for a distance approximately half way through the block. Six small holes indicated in general at 76 are drilled through the remaining portion of the block 65 above the end of the bore 75. An expansible member or chamber 78 which may be of any suitable construction and which in the modification herein shown comprises an expansible bellows, is mounted upon the block 65 and is provided with a projecting stud 80 which projects through a central opening in the block 65 and extends downwardly into physical contact with the fuse 66. The projecting stud 80 is made of suitable heat conducting material so as to conduct heat from the fuse to the material within the bellows 78.

80 A compression block 86 of suitable insulating material is bolted or otherwise suitably secured to the bottom of the block 65 and constitutes a cover for the fuse. The block 86 is provided with depressions into which the screws 67 seat and is secured to the block 65 by means of two screws that are located midway between the screws 67—67 and on opposite sides of a line joining those screws and pass into tapped holes in the block 65. The compression block 86 is provided with a rectangular slot 88 for permitting the oil or other insulating liquid within the casing 1 to circulate around the fuse. A cylindrical sleeve 89 of suitable heat insulating and electrical insulating material extends between the blocks 25 and 65 and surrounds the bellows, being spaced therefrom. The purpose of this sleeve is to limit the extent of circulation of the liquid within the casing 1 around the bellows. Thus the oil that is heated by the fuse rises into the space between the bellows and the sleeve and serves to effectively heat the bellows. In addition the sleeve prevents the accidental contact between the bellows and the studs 40—40. It is within the purview of the present invention to omit the sleeve if desired.

85 90 95 100 105 110 115 120 125 130 The bottom of the actuating or tripping rod 59 extends into a short cylindrical bore in a fitting 90 on the top of the bellows 78. The bottom of the rod 59 terminates a short

distance from the end of the bore in the fitting 90 whereby a limited amount of expansion of the bellows is permitted without producing any effect upon the rod 59. Upon 5 further expansion of the bellows the rod 59 is moved upwardly, moving the knuckle of the toggle links 51-55 upwardly to break the toggle and permit the spring contacts 45 to force the switch to snap open.

10 An explanation will now be given of the manner of operation of my improved circuit interrupter. When the switch is in the closed position a circuit extends from the conductor 6, through the terminal contact 15, through 15 the end 91 of the right hand spring contact 45, the right hand stud 40, the fuse 66 and the left hand stud 40, thence by way of the left hand spring contact 45 and the left hand terminal contact 15 through the conductor 20 within the left hand bushing. The fuse 66 is purposely made of a capacity greatly in excess of the continuous current capacity of the circuit in which it is connected. Should the load current exceed the rated amount for 25 which the fuse is designed, the fuse will commence to overheat and should the overload continue for an extended period of time the liquid adjacent the fuse will be appreciably heated. The bulk of the heated liquid will 30 rise and will act to heat the liquid within the bellows 78. In addition, the stud 80 which is in close proximity to the fuse link and therefore in the region of the hottest liquid, will conduct heat to the liquid within the bellows. 35 The bellows may be filled with oil of the same kind as is contained within the casing 1, or it may be filled with any other liquid having an appreciable coefficient of expansion at the temperatures used. Carbon tetra-cho- 40 ride, ether, or the like may be used. Upon being heated, the liquid within the bellows will expand thereby expanding the bellows. It is to be understood that the liquid within the entire casing 1 will also be heated but due 45 to the construction of the cut-out, as shown, the temperature gradient will be such that the liquid in the region of the bellows will be heated sooner and to a higher temperature than will be the rest of the body of liquid in 50 the casing 1. Upon the expansion of the liquid within the bellows the top of the bellows comes into engagement with the bottom of the actuating or tripping rod 59. Upon further expansion of the bellows the rod 59 is moved 55 upwardly thereby moving the knuckle of the toggle 51-55 upwardly and out of dead center. The spring contact members 45 being under stress now act through the members 48 and 49 to force the knuckle of the toggle up- 60 wards, the members 48 and 49 about the respective links 51 and 55 at the pins 52. The ends 91 of the contact brushes 45 thereby move out of engagement with the terminals 15, thus breaking the circuit between the conductor 6 and the corresponding conductor in

the left hand terminal bushing. It is to be noted that the tripping of the switch is dependent upon the expansion of the liquid within the bellows 79, which expansion is not dependent upon the existence of a temperature difference between the liquid within the bellows and that outside of the bellows. Thus, even if there should be a circulation of the liquid outside of the bellows, that is the liquid within the casing 1, the switch would 70 nevertheless be tripped upon the occurrence of a continuing overload. When the switch trips, the plunger 59 is moved upwardly, said plunger extending through an opening in the top 20 of casing and into a sleeve 92 which 80 is closed at its outermost end is threaded into the cover member 20.

To reset the switch, the cap portion 92 is unscrewed and the operating rod or plunger 59 is pushed downwardly. This forces the 85 contact springs 45 back into engagement with the contact 15 thereby assuming the position shown in full lines in Figure 1. In order to limit the extent of downward motion of the knuckle of the toggle comprising the links 51-55, one of the links 55 is extended beyond the knuckle as indicated at 55' and is provided with an extended portion 55a which engages the pin 52 when the links 55 and 51 reach a position of alignment. For this purpose the pin 52 is extended beyond the link 51 at one end thereof. It is thus merely necessary to depress the operating rod 59 downwardly as far as it will go in order to bring the switch into its full closed position. 90 95 100

From the description thus far given it is apparent that the distance between the bottom of the tripping rod 49 and the bellows 78 when the switch is closed will determine the extent of permissible expansion of the bellows without operating the switch. In order to vary the extent of permissible operation of the bellows the rod 59 may be adjusted lengthwise of the member 58 to bring the bottom of the rod closer to or further away from 105 the bellows. This may be accomplished by loosening the lock nut 60, if such a nut is provided, and then rotating the rod 50 to lower it. The disc 19 is calibrated as indicated at 95 and a pointer 96 is mounted upon the operating rod 59 so that upon turning of the operating rod to advance the rod towards or away from the bellows the pointer 96 moves across the calibrated scale 95 to indicate the extent of permissible operation of the bellows. 110 115 120 The pointer 96 is preferably mounted upon the rod 59 so as to be freely slidable with respect thereto to a limited extent but it is non-rotatable with respect to the rod 59. This may be accomplished by making the rod 59 125 square at its end. This will permit the free rising of the operating rod 59 when the switch is tripped. When the operating rod rises due to the tripping of the switch the pointer 96 may be held against rising by engagement 130

thereof with the cover 20. It is, of course, to be understood that any other desirable arrangement may be provided for indicating the extent of turning of the rod 59 and therefore 5 by indicating the extent to which the rod has been advanced towards or withdrawn from the bellows. As an alternative arrangement the central opening in the block member 58 need not be internally threaded. The rod 59 10 extends freely through the opening and is held in place by means of a pair of lock nuts 60—60 as shown in Figure 4. In such an arrangement it is necessary to withdraw the operating mechanism from within the casing 15 in order to adjust the rod 59 to vary the extent of permissible operation of the bellows 78.

Should an exceedingly heavy overload such as a short circuit or the like occur upon a 20 line which is being protected by my improved cut-out then the circuit will be interrupted instantly by the blowing of the fuse.

In Figure 5 I have shown a modified form 25 of bushing structure applicable to a cut-out such as shown in Figures 1 and 2. In this figure I indicate a fragmentary portion of the tank 1 and a nipple 4' press fitted into an opening therein in the same manner as is nipple 4 of the cut-out illustrated in Figure 30 2. The nipple 4' is however made of insulating material. A plug 100 provided with an iron rimmed cap 101 is screw threaded on the outside of the nipple 4'. The plug 100 may be made of suitable insulating material, such as a phenol condensation product or the 35 like molded to the cap 101. The plug is of a hollow cup-shaped configuration on the inside and is provided with an opening through which the conductor 6 may be extended. The 40 conductor 6 makes a press fit through the hole in the plug 100 so as to be liquid tight. The cup-shaped opening in the plug is filled with wads or tufts of paper which are slightly moistened with water. The wads or tufts 45 of paper 104 are then compressed by means of a disk 105 of suitable insulation, such as a phenol condensation product, which threads on the inside of the nipple 4'. The disk 105 makes a close fit with the conductor 6 thereby 50 certainly maintaining the conductor in its aligned position through the plug 100. The side of the conductor 6 that extends within the casing of the cut-out is provided with a switch contact as illustrated in Figure 2 and the opposite end extends from the nipple and is adapted to have connected thereto a suitable lead in conductor in any desired manner.

I have found that a very slight amount of moisture in the wads of paper 104 will effectively prevent creepage of oil between the disk 105 and the conductor 6 or between the disk and the inner wall of the nipple 4'. The moisture appears to act as a repellent or support for any film of oil that may commence 65 to pass through the almost microscopic spaces

that may be present. The supported film of oil therefore acts as a plug to prevent the outward passage of additional oil. A very minute quantity of moisture in the paper packing will not appreciably affect the dielectric properties of the oil to which it has only a very slight surface exposure, but it prevents the oil from passing through it outward of the cut-out casing.

In compliance with the requirements of 70 the patent statutes I have herein shown and described a preferred form of my invention. It is, however, to be understood that the invention is not limited to the precise construction herein shown, but is capable of modification within the spirit and scope of the appended claims. What I consider new and desire to secure by Letters Patent is:

1. In an electric switch comprising a closed 75 container adapted to be filled with liquid and having a hole formed therein for receiving a bushing structure, a sleeve extending through the hole and making a tight fit therewith, a tubular insulator extending into the container through said sleeve and having a flange abutting against the outside of the sleeve, said tube constituting a closure for the sleeve, a conductor extending outwardly from the container through the tube of insulation, switch contact means supported on the portion of the conductor within the container and limiting the extent of withdrawal of the conductor through the tube of insulation, and clamping means for clamping the flange of the tube of insulation against the 100 outside of the sleeve.

2. A bushing structure comprising a tube 105 of insulation, a conductor fitting tightly within the tube and extending beyond the end thereof, a switch contact secured to the extended end of the conductor and abutting against the tube for preventing the withdrawal of the extended end of the conductor through the tube, a shell member through 110 which the insulating tube extends, said tube fitting tightly within the shell member, a flange formed on said tube and spaced from the end thereof on the side of the shell opposite the terminal, said flange having tapered sides, and means for clamping the tapered sides of the flange against the shell.

3. An oil filled switch casing of smaller 115 cross section at the lower end than at the upper end, a portion of the casing affording a tapering connection between the larger and smaller ends, a nipple extending outwardly from said tapered portion, an insulating sleeve press fitted into the nipple and having a conductor extending therethrough into the casing, a guarding sleeve surrounding the outwardly extending end of the conductor and having a sliding telescoping engagement with the insulator, common clamping means for clamping both the insulating sleeve and the guard to the nipple, a contact secured to 120 125 130

and supported by the inner end of the conductor and retaining the conductor against retraction from the sleeve, and switching means within the casing movable into and out of 5 electrical engagement with the contact.

4. An electrical device including an oil containing casing, means extending through the casing, and means comprising wads of moistened paper clamped about the first named 10 means for producing an oil tight seal.

5. An electrical device including an oil containing casing, an insulating nipple extending therefrom, an electrical conductor extending through the nipple into the casing, 15 a plug carried by the nipple and making a tight fit with the conductor and including a moisture containing substance compressed about the conductor for producing an oil tight seal.

20 In witness whereof, I hereunto subscribe my name this 9 day of September, 1931.

EDMUND O. SCHWEITZER.
